[57] **CLAIM**

The ornamental design for an artificial fishing strip, as shown and described.

DESCRIPTION

FIG. 1 is a perspective view of an artificial fishing strip showing my new design with a ribbed cavity configuration formed on a top surface thereof;

FIG. 2 is a front elevational view of the design shown in FIG. 1;

FIG. 3 is a top view of my design shown in FIG. 1;

FIG. 4 is a bottom view of my design shown in FIG. 3; and

FIG. 5 is a side elevational view of my design shown in FIG. 5.

FIG. 2

FIG. 3

FIG. 4

FIG. 5
